DESIGN FOR A SCALP LOTION ATOMIZER OR SIMILAR DEVICE

Robert Gordon Mills, Winnetka, Ill.

Application March 27, 1935, Serial No. 56,072

Term of patent 7 years

To all whom it may concern:

Be it known that I, Robert Gordon Mills, a citizen of the United States, residing at Winnetka, in the county of Cook and State of Illinois, have invented a new, original, and ornamental Design for Scalp Lotion Atomizer or Similar Device, of which the following is a specification, reference being had to the accompanying drawing, forming part thereof.

In the drawing

Fig. 1 is a side elevational view of a scalp lotion atomizer embodying my design;

Fig. 2 is a top plan view thereof;
Fig. 3 is a front elevational view thereof; and
Fig. 4 is a rear elevational view thereof.

I claim:

The ornamental design for a scalp lotion atomizer, or similar device, as shown.

In witness whereof, I hereunto subscribe my name this 20th day of March, 1935.

ROBERT GORDON MILLS.
